UNITED STATES PATENT OFFICE.

ANTHONY SCHROEDER, OF CLEVELAND, OHIO, ASSIGNOR OF ONE-HALF TO JAMES MERLE FINNEY, OF CLEVELAND, OHIO.

DISPENSING MECHANISM.

Application filed December 11, 1922. Serial No. 606,156.

To all whom it may concern:

Be it known that I, ANTHONY SCHROEDER, a citizen of the United States, residing at Cleveland, in the county of Cuyahoga and

5 State of Ohio, have invented certain new and useful Improvements in and Relating to Dispensing Mechanism, of which the following is a specification.

This invention relates to a dispensing 10 mechanism for liquids. In practical use of my invention I have applied it to the dispensing of relatively heavy liquids, such as lubricating oils.

One object of the invention is to provide 15 an improved mechanism of this character which is relatively simple and lends itself to economical manufacture and easy assembly and disassembly.

Another object of the invention is to provide 20 an improved dispensing mechanism in which the elements may be adjusted to different relative positions, at will, while at the same time permitting ready assembly upon or in the liquid container.

25 A further object of the invention is to provide a liquid dispensing mechanism in which the supporting elements for the dispensing means are constructed to serve as a drain pipe through which the surplus or 30 spilled oil may flow back into the container through the opening therein for the delivery pipe, but independently thereof.

Other objects will be apparent to those skilled in the art to which my invention relates 35 from the following description taken in connection with the accompanying drawing, wherein—

Fig. 1 is an elevational view (partly in section) of a dispensing mechanism embodying 40 my invention.

Fig. 2 is a fragmentary view, slightly enlarged.

Fig. 3 is a section on the line 3—3 of Fig. 2.

45 Figs. 4 and 5 are detail sectional views of the supporting elements.

Fig. 6 is an elevational view (partly in section) of the pump cylinder and discharge nozzle.

50 In the drawings, 1 indicates a container

which may be of any desired construction and shape, but preferably comprising a barrel or drum formed from sheet metal, having heads connected with the body portion of the barrel in a liquid-tight manner, for 55 instance, by a double seam. The upper head 1^a of the drum is formed with one or more openings 2, in one of which is fitted a collar 3, being secured therein in any well known way. The inner wall of the collar 60 3 is provided with screw threads to receive a plug (not shown), whereby the opening may be sealed for shipping and other purposes.

4 indicates as an entirely a dispensing 65 means, such as a pump of any desired construction. In the chosen illustrated example, I have shown a reciprocating piston type of pump, constructed to suck from the container 1 and discharge from its nozzle 4^a 70 a predetermined quantity of oil or other liquid at each operation. The pump 4 comprises a cylinder 4^b in which a piston 5 (shown in dotted lines in Fig. 1) reciprocates, the rod 6 for the piston being guided 75 to move into and out of a tubular extension 4^c. 7 indicates an operating member—such as a crank—preferably operatively connected with the rod 6 by one or more gears and a rack (not shown). The head 4^d at the lower 80 end of the cylinder 4^b is formed with a central opening 4^e, the inner wall of which is screw threaded. 8 indicates a pipe extending through the collar 3 into the container 1, its upper end being screw threaded into 85 the opening 4^e in the cylinder head 4^d and rigidly connected thereto. As will be understood from Fig. 1, the pipe 8 extends through the opening 2 in the drum or container 1 and downwardly to or adjacent its 90 bottom, for well known reasons.

8^a indicates a discharge nipple projecting from one side of the cylinder head 4^d, the walls of the nipple preferably being formed integrally with the cylinder head. Near its 95 outer end, the inner wall of the nipple is provided with an annular rib 8^b, which forms a discharge port for the liquid and a seat for a valve 8^c. As will be understood, the valve 8^c engages its seat to close 100

the port during the suction stroke of the piston 5. The inner end of the nozzle 4^a is adjustably mounted on or connected to the outer end of the nipple 8^a, whereby its outer or discharge end may be moved to any desired position relative to the pump cylinder 4^b, or the crank 7, or a support 11, to which reference will later be made. The adjustable connections for securing the nozzle 4^a on or to the nipple 8^a preferably comprise the following instrumentalities: 4^f indicates screw threads provided on the outer surface of the nozzle 4^a near or adjacent its inner end. 8^d indicates a collar screw threaded on the inner end of the nozzle and arranged to seat against the end wall of the nipple 8^a. As shown, the collar 8^d is disposed at a point remote from the end of the nozzle 4^a so that its end may extend 20 into the nipple 8^a and form a stop to limit undue movement of the valve 8^e during the force stroke of the piston 5. 8^e indicates a coupling adapted, through the screw thread connection shown at 8^f, to engage the collar 8^d and clamp it against the end wall of the nipple. By loosening the coupling 8^e, the nozzle 4^a and collar 8^d may be rotated or adjusted to arrange the outer end of the nozzle in the desired position. A gasket 8^g 30 may be provided between the collar 8^d and the end wall of the nipple 8^a, to prevent leakage through the joint or connection. The inner end of the nozzle 4^a is cut away at opposite sides, as shown at 4^{a'}, to provide escape passages from the nipple into the nozzle during the discharge of the liquid; otherwise, the pressure of the liquid against the valve might cause the latter to close the inner end of the nozzle and thus shut 40 off the flow of the liquid. The adjustable connections for the nozzle 4^a permit its ready removal and access to the valve 8^e.

9, 10, indicate a pair of elements arranged co-axially and adapted to support the dispensing means 4 on the container 1 and the support 11 for a receptacle (not shown) that is to be filled with oil or other liquid. The support 11 preferably comprises a circular shaped casting having a wall 11^a that is inclined downwardly and inwardly from its circumferential edge, a centrally arranged chamber 11^b and ribs 11^c extending from the outer edge of the chamber 11^b to the circumferential edge of the casting. The upper edges of the ribs 11^c are horizontally disposed so as to properly support the receptacle to be filled, while permitting the spilled or surplus oil to flow or drain from the wall 11^a into the chamber 11^b. At 11^d the walls of the casting are thickened and formed with an opening 11^e, which serves as a conduit leading from the chamber 11^b.

12 indicates a screen that may be pro-

vided in the chamber 11^b. 13 indicates a pipe having screw threaded connection at its outer end with the inner wall of the conduit 14. The inner end of the pipe 13 is threaded into the outer end of an opening 10^a formed in and extending through one side wall of the supporting element 10.

The supporting element 9 comprises a tubular member surrounding the pipe 8 and forming with its outer surface a conduit 14. The lower end of the tubular member is preferably reduced and provided with screw threads which fit the screw threads formed on the inner wall of the collar 3, thereby permitting the tubular member 9 to be rigidly supported in the collar 3.

The inner wall of the tubular member 9 is provided with longitudinally extending spaced ribs 9^a, which engage the pipe 8 and maintain it and the tubular member in concentric relation. At one side, the tubular supporting element 9 is formed with a screw threaded opening 9^b to receive a set screw 15, adapted to be tightened against the pipe 8 to rigidly connect it and the tubular member together, so that the latter may rigidly support the pipe 8 and dispensing means 4 in the position shown in Fig. 1. At

its upper end, the tubular member 9 is formed with an annular recess 9^c, which provides a seat and a bearing for the lower reduced end of the supporting element 10, whereby the latter may be rotated to different positions about the pipe 8 and relative to the supporting element 9 to arrange the support 11 below or at either side of the nozzle 4^a. The supporting element 10 comprises a collar the inner wall of which co-operates with the outer wall of the pipe 8 to form a continuation of the conduit 14, so as to provide a liquid connection from the pipe 13, through the opening 10^a, to the drum or container 1. By this arrangement, the oil draining from the support 11 is conducted, independently of the pipe 8, that is, the oil flowing therethrough to the dispensing means 4, back to the container 1 and to or on top of the oil therein, so that if there is any dirt in this returning oil, it will not get into that portion of the oil that is being dispensed. The upper end of the collar 10 is provided with an inwardly extending flange 10^b, which engages with the pipe 8. The flange 10^b serves to rotatably support the upper end of the collar 10 on the pipe 8 and also forms an end wall for the conduit 14, it co-operating with the bearing 9^c in the tubular member 9 to permit adjustments of the collar, as already set forth. The inner wall of the collar 10 is provided with longitudinally extending spaced ribs 10^c, which engage the pipe 8 and thus serve to maintain the collar concentric thereto. The ribs 10^c terminate at a point

below the opening 10^a, so that the oil draining through or from the pipe 13 may enter any or all of the passages between the ribs and freely escape. At one side, the 5 collar 10 is formed with a screw threaded opening 10^d, through which a suitable set screw extends, whereby its free end may be caused to engage the pipe 8 and thereby secure the collar 10 thereto in the position 10 to which it is adjusted.

In constructions of dispensing mechanisms of which I am aware, the dispensing means and the receptacle support had a fixed relation to the pipe or sleeve member which 15 was secured in the collar in the container opening. As a result these means and elements had to be arranged according to the position in which the pipe or sleeve member came to rest when it was tightened in the 20 container opening, thus preventing adjustment of the dispensing means and the receptacle support either relative to the container or relative to each other.

I have sought to overcome these disadvantages by providing a pair of relatively movable supporting elements, so that one thereof may be fixed in the container opening while the other may be moved to permit of the necessary and desired adjustments of the 25 dispensing means and receptacle support. From the foregoing description it will be noted that the collar 10, the receptacle support 11 and dispensing means 4 are carried by that supporting element which is rigidly 30 fixed in the container opening; also, that the dispensing means 4 and the delivery pipe therefor and the support 11 and the collar 10 may be removed as a unit and assembled 35 as a unit from and in the supporting member 9, in a ready manner; or these elements may be adjusted about the axis of the collar 3 by loosening the set screw 15, to arrange the dispensing means 4 or its nozzle 4^a in any desired position. Likewise, by loosening 40 the set screw 16, the support 11 may be swung about the pipe 8 relative to the supporting element 9, to any desired position. When the set screws 15 and 16 are tightened, it will be noted that the collar 10 is 45 fixed to the pipe 8 and that the latter is fixed to the tubular member 9; accordingly, these elements and the dispensing means 4 and support 11 may be assembled as a unit 50 in the opening in the container head 1^a, and also removed therefrom in the same manner, so that when the oil in one container has been 55 completely dispensed, these parts may be removed and assembled in the opening in a container that is full.

60 The construction is such that the pump cylinder and receptacle support may be adjusted independently of each other, irrespective of the position of the supporting element 9 when it is tightened in the collar 3,

it being desirable to tighten the supporting 65 element 9 in the collar 3 so that the pump 4 and support 11 may be rigidly held in position for operation. Furthermore, it will be noted that the nozzle 4^a is adjustable relative to the pump cylinder. As a result, my 70 construction of dispensing mechanism permits the container to be placed at any desired point and thereafter the pump cylinder, receptacle support and nozzle to be adjusted to bring any one or all thereof into the 75 most convenient position for manipulation.

In carrying out my invention and accomplishing these advantages, I provide for the drainage of spilled oil from the receptacle support back into the container through the 80 same opening into which the delivery pipe extends, thereby making it unnecessary to provide separate openings in the container for this purpose.

To those skilled in the art to which my invention relates, many alterations and modifications of the invention and applications thereof will suggest themselves without departing from the spirit and scope thereof. The description and the disclosures herein 90 are purely illustrative and are not intended to be in any sense limiting.

What I claim is:

1. In a dispensing mechanism, the combination with a container formed with an opening in one wall thereof, of dispensing means, a delivery pipe extending through said opening and connected to said dispensing means, a support adapted for correlation with the nozzle of said dispensing means, devices for supporting said dispensing means and said support, said devices comprising a pair of relatively movable upper and lower members, means for connecting said support to said upper member, means for securing said pipe to said lower member, and separate means for adjustably securing said upper member to said pipe. 95

2. In a dispensing mechanism, the combination with a container formed with a screw threaded opening in one wall thereof, a dispensing means, a delivery pipe extending through said opening and connected to said dispensing means, a support adapted for correlation with the nozzle of said dispensing means, devices for supporting said dispensing means and said support, said devices comprising a pair of upper and lower relatively movable members, the said lower member being screw threaded into said opening, means for connecting said support to said upper member, means for securing said pipe to said lower member, and separate means for adjustably securing said upper member to said pipe. 100

3. In a dispensing mechanism, the combination with a container formed with an opening in one wall thereof, of a dispens-

ing means, a delivery pipe extending through said opening and connected to said dispensing means, a support adapted for correlation with the nozzle of said dispensing means, devices for supporting said dispensing means and said support, said devices comprising a pair of relatively movable upper and lower members surrounding said pipe and co-operating to form a conduit therearound leading through said container opening independently of the flow of liquid through said pipe, means for supporting said lower member in said container opening, means for securing said pipe to said lower member, separate means for adjustably securing said upper member to said pipe, and a connection between the bottom of said support and said conduit through which spilled liquid drains thereto.

20 4. In a dispensing mechanism, the combination with a container having an opening through one wall thereof, of a dispensing means, a delivery pipe extending through said opening and connected to said dispensing means, a support for a receptacle to be filled by said dispensing means, a pair of co-axially arranged members surrounding said pipe, the lower member being fixedly supported in said opening and the upper member rotatively engaging said lower member and said pipe and carrying said support, and means for adjustably securing said upper member to said pipe.

25 5. In a dispensing mechanism, the combination with a container having an opening through one of its walls, of a dispensing means, a delivery pipe extending through said opening and connected to said dispensing means, a support for a receptacle to be filled by said dispensing means, a pair of co-axially arranged members surrounding said pipe and correlated therewith to form a conduit extending through said opening, the lower member being fixedly supported

30 40 45 50 55 60 65 70 75 80 85 90 95 100 105 110 115 120 125

in said opening and the upper member rotatably engaging said lower member, a flange carried by said upper member rotatably engaging said pipe and forming an end wall for said conduit, a pipe between the bottom of said support and said upper member for supporting said support and conducting spilled liquid therefrom to said conduit, and means for adjustably securing said upper member in fixed relation to said dispensing means.

66 6. In a dispensing mechanism, the combination with a container having an opening in one of its walls, of a dispensing means, a delivery pipe extending through said opening and connected to said dispensing means, a support for a receptacle to be filled by said dispensing means, a pair of co-axially arranged members surrounding said pipe and correlated to form a conduit around

said pipe and extending through said container opening, the lower member being fixedly supported in said opening and the upper member rotatably engaging said lower member, ribs arranged between said pipe and said members for maintaining them concentric to said pipe, a flange carried by said upper member rotatably engaging said pipe and forming an end wall for said conduit, a pipe connected to said upper member and the bottom of said support for supporting the latter and conducting spilled liquid therefrom to said conduit, and means for adjustably positioning said upper member in fixed relation to said dispensing means.

7. In a dispensing mechanism, the combination with a container having a screw threaded opening in one of its walls, of a tubular member screw threaded into said opening, a dispensing means, a delivery pipe extending through said tubular member into said container and connected to said dispensing means, means between said pipe and said tubular member for maintaining them in spaced relation to form a conduit through said member into said container, a collar surrounding said pipe and co-operating with said tubular member to form a continuation of said conduit, the upper end of said collar being provided with a flange engaging said pipe to form an end wall for said conduit, a support for receptacles carried by and having a liquid connection through the wall of said collar with said conduit for drainage purposes, and means for adjustably connecting said collar to said pipe.

8. In a dispensing mechanism, the combination with a container having a screw threaded opening in one of its walls, of a tubular member screw threaded into said opening, a dispensing means, a delivery pipe extending through said tubular member into said container and connected to said dispensing means, means between said pipe and said tubular member for maintaining them in spaced relation to form a conduit through said member into said container, a collar surrounding said pipe and co-operating with said tubular member to form a continuation of said conduit, the upper end of said collar being provided with a flange engaging said pipe to form an end wall for said conduit, a support for receptacles carried by and having a liquid connection through the wall of said collar with said conduit for drainage purposes, means for adjustably connecting said collar to said pipe, and means for detachably connecting said pipe to said tubular member.

9. In a dispensing mechanism, the combination with a container formed with an opening in one wall thereof, of dispensing means, a delivery pipe extending through said opening and connected to said dispens-

ing means, a nozzle adjustably connected to said dispensing means, a support adapted for correlation with the said nozzle, devices for supporting said dispensing means and
5 said support, said devices comprising a pair of relatively movable members disposed one above the other, means for connecting said support to said upper member, means for securing said pipe to said lower member, and separate means for adjustably securing said 10 upper member to said pipe.

In testimony whereof, I have hereunto
subscribed my name.

ANTHONY SCHROEDER.
